UNITED STATES PATENT OFFICE.

MASON B. GIBERSON, OF DETROIT, MICHIGAN, ASSIGNOR TO MONARCH STEEL CASTINGS COMPANY, OF DETROIT, MICHIGAN, A CORPORATION OF MICHIGAN.

BOLSTER.

1,132,576.

Specification of Letters Patent. Patented Mar. 23, 1915.

Application filed July 11, 1914. Serial No. 850,450.

To all whom it may concern:

Be it known that I, MASON B. GIBERSON, a citizen of the United States of America, residing at Detroit, in the county of Wayne 5 and State of Michigan, have invented certain new and useful Improvements in Bolsters, of which the following is a specification, reference being had therein to the accompanying drawings.

10 The invention relates to railway trucks and particularly to the construction of the bolster for transmitting the load to the side frames.

15 It is the object of the invention to obtain maximum strength with minimum weight, and to this end the invention consists in the construction as hereinafter set forth.

In the drawings: Figure 1 is a cross section through a truck frame showing the bolster in elevation; Fig. 2 is a cross section of the bolster on line α — α Fig. 1; Fig. 3 is a side elevation of a portion of the truck frame showing the bolster in end elevation; and Fig. 4 is a plan view of the bolster.

20 25 A is one of the side frames of the truck, which is provided centrally with an aperture B through which the end of the bolster may be inserted.

30 35 C is the bolster, which has an enlarged central portion tapering toward the opposite ends. At the center is formed a tubular core portion D for receiving the king bolt of the truck, and at the opposite ends are flanges E for slidably engaging vertical guides F on the side frames.

It is usual to form bolsters of a cross section which is either that of an I-beam or a

box girder; that is with either a central vertical web or two vertical webs at the opposite sides. I have found that with the same 40 weight of metal a much stronger construction may be obtained by forming the bolster of a cross section having three vertical webs, one at the center and two at the respective sides. Thus, as shown, G is the central web 45 and G' and G² are the side webs which extend between the top H and the bottom H', being cast integral therewith. These webs may be centrally cut away at I upon opposite sides of the center of the bolster to reduce the weight without weakening the 50 structure. However, the portion of the central web immediately adjacent to the tubular core portion D extends continuously from top to bottom and forms a longitudinal reinforcement for said core, while a transverse web J extending between said core and the 55 opposite side webs G' and G² form a transverse brace.

What I claim as my invention is:—

A bolster for railway trucks tapering in a vertical plane from center to opposite ends and comprising continuous top and bottom webs, and parallel side and center webs integrally connected with said top and bottom 60 webs and substantially continuous therewith in cross section.

In testimony whereof I affix my signature in presence of two witnesses.

MASON B. GIBERSON.

Witnesses:

JAMES P. BARRY,
HENRIETTA E. BOWMAN.
